COMBINED HANDLE AND HOLDER FOR A BLADE

Peter James Craddock, Woodside, S3 9PD,
Sheffield, England

Filed Nov. 27, 1972, Ser. No. 309,759

Claims priority, application Great Britain May 26, 1972

Term of patent 14 years

Int. Cl. D8—05

U.S. Cl. D8—98

FIG. 1.

FIG. 2.

FIG. 3.

FIG. 4.

FIG. 5.

FIG. 6.

FIG. 1 is a side elevational view of a combined handle and holder for a blade embodying my new design;

FIG. 2 is a side elevational view showing the opposite side of the handle and holder of FIG. 1;

FIG. 3 is a top plan view thereof;

FIG. 4 is a bottom plan view thereof;

FIG. 5 is a left-end elevational view of the handle and holder of FIG. 1; and

FIG. 6 is a right-end elevational view of the combined handle and holder of FIG. 1.

I claim:

The ornamental design for a combined handle and holder for a blade, as shown.
